UNITED STATES PATENT OFFICE.

ANTON POLICHEK, OF CHICAGO, ILLINOIS.

MECHANICALLY-OPERATED FIGURE TOY.

Application filed February 19, 1925. Serial No. 10,167.

To all whom it may concern:

Be it known that I, ANTON POLICHEK, a citizen of the United States, residing at Chicago, in the county of Cook and State of Illinois, have invented certain new and useful Improvements in Mechanically-Operated Figure Toys, of which the following is a specification.

This invention relates generally to toys, having more particular reference to a toy comprising a pair of moving figures representing blacksmiths working at an anvil, the invention being here embodied in a toy arranged for hand manipulation.

The present invention has for an object to provide a novel and interesting toy that may be cheaply manufactured.

For further comprehension of the invention, and of the objects and advantages thereof, reference will be had to the following description and accompanying drawing, and to the appended claims in which the various novel features of the invention are more particularly set forth.

Fig. 1 of the drawing is a side elevational view of my improved toy.

Fig. 2 is a plan view thereof.

Fig. 3 is a fragmentary central longitudinal sectional view thereof.

Fig. 4 is a detail transverse sectional view taken on the line 4—4 of Fig. 3.

Referring now to the drawing, the improved toy comprises a pair of figures or mannikins 10 each formed to represent the body of a smith. These figures are positioned facing one another, being held in the given general relation by means of a pair of parallel bars 11 and 12. These bars are arranged one above the other, in close adjacency to one another, and are straddled at their ends by the bifurcated lower ends 10' of the figures. The figures are attached to the bars 11 and 12 to permit of swinging with relation to the latter, by means of pins 14 that pass freely through the said bars and are fixed at their ends in the said bifurcated portions of the figures. The top bar 11 is formed midway between its ends with an upward projection 15 that constitutes the anvil. This bar is extended longitudinally behind and beyond one of the figures, in the form of a handle 11' while the other bar is similarly extended behind the other figure in the form of a handle 12'.

Each figure carries a hammer comprising a head 18 and a handle 19, the head being

so positioned to strike the anvil when the hammer is swung up and down. The handle of each hammer is preferably formed rigid with a pair of arm extensions 20 from the respective figures, these arm extensions being fixed to shafts 21 pivoted in the shoulder portions of the figures. These shafts 21 have fixed thereto the short arms 22 that are located in recesses 23 that extend upward within the figures from the bifurcated lower ends of the latter. These arms have connected thereto the upper ends of the links 24 that extend downward through the recesses in the figures and through slotted apertures 25 in the bars 11 and 12 and are pivotally connected at their lower ends to the lower bar 12 as at 26 the points of connections of the links to the said bar being forwardly of the pins 14 that serve to pivotally connect the figures to the bars. The arms 22 may have also connected thereto the tension springs 28 that are attached to the shoulder portion of the said figures.

The toy is used by grasping the handle elements 11' and 12' and moving the hands of the user toward and away from one another, causing the bars 11 and 12 to move longitudinally upon one another. This longitudinal movement of the bars imparts a swinging movement to the figures, while in addition it causes the arms 20 to swing on the figures, moving the hammers 18 up and down.

Having thus described my invention, what I claim as new and desire to protect by Letters Patent of the United States is as follows:

1. A toy comprising a pair of figures arranged in opposition to one another, and a pair of parallel bars to which said figures are pivotally attached, said bars being arranged one above the other, and said figures being bifurcated to straddle the ends of the said bars, arms hinged to the said figures, hammers carried by the said arms, and operative connections between the said arms and one of the said bars whereby the said arms are caused to swing on the figures when the said bars are moved longitudinally upon one another.

2. A toy comprising a pair of parallel bars arranged in close adjacency one above the other, a pair of figures facing one another and having bifurcated lower ends straddling the ends of the said bars and pivotally connected thereto, shafts pivoted in the shoul-

der portions of the respective figures, arms fixed to said shafts, hammers carried by the said arms, a projecting arm on each of said shafts within the said figures, and links connecting the said last named arms with the one of said bars.

3. A toy comprising a pair of parallel bars arranged in close adjacence one above the other, a pair of figures facing one another and having bifurcated lower ends straddling the ends of the said bars and pivotally connected thereto, shafts pivoted in the shoul-

der portions of the respective figures, arms fixed to said shafts, hammers carried by the said arms, a projecting arm on each of said shafts within the said figures, and links connecting the said last named arms with the one of said bars, the top one of said bars having a projection on its top face midway between its ends simulating an anvil.

In testimony whereof I have affixed my signature.

ANTON POLICHEK.
